DEODORIZER FOR AUTOMOBILES AND THE LIKE

Leonard A. Irving, 723 W. Pratt St., Baltimore, Md.

Filed Nov. 15, 1962, Ser. No. 72,503

Term of patent 3½ years

(Cl. D16—2)

Fig. 1

Fig. 2

Fig. 3

FIG. 1 is a front elevation of a deodorizer for automobiles and the like embodying my new design;

FIG. 2 is a rear elevational view thereof; and

FIG. 3 is a side elevational view thereof.

The side not illustrated is identical to the side shown.

I claim:

The ornamental design for a deodorizer for automobiles and the like, as shown and described.
